UNITED STATES PATENT OFFICE.

WILLIAM C. FRITZ, OF CHICAGO, ILLINOIS.

SCAFFOLD.

1,033,389.

Specification of Letters Patent. Patented July 23, 1912.

Application filed November 8, 1911. Serial No. 659,088.

To all whom it may concern.

Be it known that I, WILLIAM C. FRITZ, a citizen of the United States, and residing at Chicago, in the county of Cook and State of Illinois, have invented a new and useful Improvement in Scaffolds, of which the following is a complete specification.

The main objects of this invention are to provide an improved scaffold; to provide a scaffold adapted to be adjusted as to length and as to height; to provide novel mechanism for supporting and adjusting the scaffold vertically; and to provide a strong and durable construction adapted to 15 be folded into small compass when not in use.

The invention consists of the matters hereinafter described and more fully pointed out and defined in the appended claim.

20 In the drawings: Figure 1 is a fragmentary perspective view of a scaffold embodied in this invention with the extension legs at one end shown in dotted lines in position to be adjusted and also extended. Fig. 2 is a fragmentary side elevation of the scaffold in folded position. Fig. 3 is an 25 end elevation of the scaffold. Fig. 4 is a fragmentary, side elevation of a modified form of the scaffold. Fig. 5 is a side elevation 30 of one of the cross bars for the inner legs of the construction shown in Fig. 4.

As shown in the drawings: Referring first to Figs. 1 to 3 inclusive, the scaffold is provided with a longitudinally extensible platform, comprising a central section 1 and end sections 2 and 3. Each section comprises side members or stringers 4 which taper from their under edges upwardly toward their ends, and on which are cross 35 boards 5. The central section 1 is provided with transverse cleats 6 extending across the bottom thereof, and the end sections, which are narrow enough to slide between the stringers of the central section, 40 are slidably mounted at their inner ends on said cleats, and are provided on their inner ends with transverse cleats 7, adapted when fully extended to abut against the cleats 6 and prevent the end sections from being 45 withdrawn from the central section. Any desired means may be employed to hold the end sections in adjusted position. The central section 1 is provided on each end with a metal reinforcing band 8 which is bent 50 down at its ends to overlap the stringers, and is secured thereto.

The main legs 9 are pivoted at their upper ends to the end sections 2 and 3, near the outer ends thereof, by means of rods 10. Connecting the two legs at each end of the scaffold are cross bars 11 which are spaced a distance apart, and the outer ends of which are flush with the outer sides of the legs. The lower ends of said legs are wider than the remaining portion to provide feet 12 60 adapted to give greater stability to the structure.

Slidably mounted on the outer sides of the legs 9 are the extension legs 13, which are also connected together by cross bars 70 14 adapted to alternate with the cross bars 11, so that one bears or rests on the other. The legs 13 are provided at their upper ends, above the upper cross piece 14, with hooks 15 which hook around the front edges 75 of the legs 9 and prevent the upper ends of the legs 13 from tipping outwardly.

Braces 16 are pivoted at their rear ends to the inner sides of the legs 9 and extend upwardly and inwardly and are hooked to 80 pins 17 on the sides of the sections 2 and 3. A bar 18 is pivoted to each brace 16 and extends toward the legs and is adapted to hook onto a pin 19 on the inner side of the leg 9. The bars 18 provide steps to be used 85 when mounting the scaffold. The legs 9 and 13 are provided with registering apertures 20 adapted to receive pins to hold the legs in proper relation.

In the construction shown in Figs. 1, 2 90 and 3, the scaffold is adapted to be raised above the height of the legs 9. In the construction shown in Fig. 4 the platforms are adapted to be lowered on the legs 9. In this latter construction the legs 13 are connected 95 together by cross bars 21, which are of less width than the bars 14, and are provided with notches 22 in which notches 23 in the stringers of the end section engage, and the legs 9 are connected together by bars 24 on 100 which the bars 21 rest.

The operation is as follows: In the construction shown in Figs. 1, 2 and 3, the platforms may be extended longitudinally by adjusting the end sections in the central 105 section. When it is desired to raise the platform to a greater height than that afforded by the legs 9, the lower ends of the legs 13 are swung outwardly, as shown in dotted lines in Fig. 1, until the bars 14 110 clear the bars 11. The outer legs 13 may then be moved downwardly and swung back

to place to permit the bars 11 to rest on the bars 14. When the scaffold is not in use the legs may be folded under the platform as shown in Fig. 2.

5 In the construction shown in Fig. 4 the platform may be supported on any of the bars 21.

Obviously many details of the constructions shown may be varied or omitted without departing from the scope of the claim.

I claim:

A scaffold comprising an extensible platform, main legs hinged to the platform, extension legs slidably mounted on said main legs, cross bars connecting each pair of main legs together, and each pair of ex-

tension legs together, the cross bars of the main legs being adapted to be superimposed on the cross bars of the extension legs, retaining hooks on the extension legs adapted to allow the lower portions to swing out for adjustment, and braces on the main legs removably connected to the platform, substantially as set forth.

5 In testimony whereof I have hereunto 25 subscribed my name in the presence of two witnesses.

WILLIAM C. FRITZ.

Witnesses:

JOSEPH SCHLENKER,
ROBT. KLOTZ.
